UNITED STATES PATENT OFFICE.

JOSEPH BREWER, OF NEW YORK, N. Y.

KEY HOLDER.

Application filed May 5, 1925. Serial No. 28,164.

This invention relates to key holders of that character in which a plurality of keys may be conveniently supported for use on the carrier therefor attached to a flexible and foldable cover, which embodies means for displaying an identification card.

One of the objects of the present invention is the production of a key holder as characterized hereinbefore, which may be carried about suspended from a belt or other apparel accessory, as an extra advantage of carrying the key holder about under unusual circumstances, such as when a person is not wearing a coat or objects to carrying a key holder in the pocket which results in portions of the garments becoming frayed and torn.

Another object of the invention is to make provision in a key holder as characterized hereinbefore for protecting an identification card so as not to be mutilated or obliterated by the keys, thereby insuring identification of the owner.

With these and other objects in view, the invention resides in the particular provision and construction of parts hereinafter fully described and illustrated in the accompanying drawings, in which:

Figure 1 is a view of the key holder embodying the present invention and shown in an open condition;

Fig. 2 is a detail sectional view taken on the line 2—2 of Fig. 1 and looking in the direction of the arrows;

Fig. 3 is a sectional view taken on the line 3—3 of Fig. 1, looking in the direction of the arrows;

Fig. 4 is a view similar to that shown in Fig. 2, but showing a modification of the construction of the carrier.

Referring now more particularly to Figures 1, 2 and 3 of the drawing, it will be apparent that the key holder of the present invention includes a cover 10 of some suitable flexible material, such as leather, which is capable of being readily folded with portions overlapping each other to be fastened, the overlapping portions being fastened to each other. The fastening of the overlapping portions is accomplished by the use of co-operable fasteners 11 and 12 carried by portions of the cover 10. For supporting or suspending the keys, there is provided a carrier 13. The carrier 13 in the present instance, is stamped, bent, and formed from a single piece of material, preferably metal,

to provide a substantially rectangular body 14, loop 15, opening 16 in the body 14, flange 17 adjacent one longitudinal edge of the opening 16, said flange having a series of 60 holes 18 therein, a clip 19 extending into the opening 16, and a hole 20. Portions of the body 14 and loop 15 are turned as at 21, to provide a smooth finish for these portions of the carrier, and to lend rigidity thereto. 65 The loop 15 at one side of the opening therein is thickened as at 22 by returning the metal to provide a substantial wear portion. The flange 17 is turned as at 23, to provide a smooth finish surface for the edge thereof. 70 The carrier 13 is attached to the cover 10 in any preferred manner, and in the present instance is attached to the cover by suitable rivets 24.

In order that the owner of the key holder 75 may be made known in the event that the same is lost, an identification card 25 may be placed between portions of the body 14 at the opening 16, and the adjacent portion of the cover 10, as shown most clearly in Fig. 2. 80 Owing to the manner in which the carrier is attached to the cover 10, the card 25 may be readily moved in position to display the information on the card through the opening 16. In order to protect the printed face 85 of the card 25, there is provided a flexible flap 26 of transparent material, such as celluloid, the same being attached to the carrier in the present instance, by two of the rivets 24. The free longitudinal edge of the 90 flap 26 is disposed between the adjacent portion of the body 14 and the cover 10, as shown most clearly in Fig. 2. The clip 19 is disposed under a portion of the flap 26, to aid in inserting the free edge of the flap 26 95 between a portion of the body 14 and a portion of the cover 10, since the flap 26 will be flexed. A portion of the card 25 is similarly flexed. The flexing of the flap and card insures a close relationship between 100 them and the card indicia is therefore more readable. If desired, the card 25 and protecting flap 26 may be held in place by bending a portion of the body 14 back upon itself as shown in the modification in Fig. 4. It 105 will be noticed that the card 25 and transparent cover 26, are held between the turned portion 27 and a portion 28 at one side of the body 14, and at the opposite side they are held between a portion 29 of the 110 body and a portion of the cover 10.

From the foregoing it will be apparent

that provision is made for supporting or suspending the holder from a suitable hook carried by the person, which will be engageable with the loop 15; that if a chain be used its free end may be releasably connected to the loop 15 by virtue of the hole 20; that numerous keys either on swivels or rings, may be suspended from the flange 17 by virtue of the holes; that the owner may be easily identified by virtue of the card 25 at all times protected against obliteration, and that the carrier with its keys will be enclosed by the cover 10 and protected against moisture, etc., with the loop extended beyond the cover for the purpose mentioned.

What is claimed is:

1. A key holder comprising a cover of foldable material, a key carrier attached to said cover, said carrier being stamped, bent and formed from a single piece of material to provide a loop, and a flange having a series of holes therein by virtue of which the

keys are suspended, said loop extending beyond said cover.

2. A key holder comprising a cover of foldable material, a key carrier attached to said cover, said carrier being stamped, bent and formed from a single piece of material to provide a loop, a flange having a series of holes therein by virtue of which the keys are suspended, and a clip extending into an opening; and a transparent flap carried by said carrier and disposed to lie over said opening with a portion thereof flexed by said clip and the free edge of the flap inserted between a portion of the carrier and a portion of the cover.

3. For supporting a multiplicity of keys, a carrier stamped, bent and formed from a single piece of material to provide a body having an opening therein, a loop, and a flange having a series of holes therein, said flange bordering said opening.

JOSEPH BREWER.
